UNITED STATES PATENT OFFICE.

EDWARD T. MICKEY, OF WINSTON-SALEM, NORTH CAROLINA.

IRONING BOARD.

Application filed December 26, 1925. Serial No. 77,766.

My invention relates to ironing boards, and more especially to that type of ironing board adapted to be built into houses when they are constructed, or fitted into a hole 5 sawed in the wall of any house, and so constructed as to fold up into a small space and be hidden from view when not in use.

Another object of my invention is to provide a cabinet ironing board having two 10 ironing boards therein, one of the boards being adapted to be used for ironing large garments and the other board being adapted for use in ironing the sleeves of garments, and smaller garments.

Another object of my invention is to provide in an ironing board pivoted members 15 folding into a cabinet when not in use, each board being provided with a slide on its lower face in which the end of another pivoted member slides.

Having thus stated some of the objects of my invention, other objects will appear as the description proceeds.

A brief description of the different figures in the drawings will now be given in which:

Figure 1 is a perspective view of my device in open position and ready for use;

Figure 2 is a side elevation partially in 20 section of the ironing board, showing it in open position;

Figure 3 is a vertical sectional view of the device showing it in closed position, and taken along the line 3—3 in Figure 5;

Figure 4 is a front elevation of my device, showing the door of the cabinet open and the pivoted ironing boards in closed position;

Figure 5 is a front elevation of my device 40 showing the cabinet with the door closed;

Figure 6 is a cross-sectional view taken along the lines 6—6 in Figure 2;

Figure 7 is a side elevation partially in 45 section of a portion of the sleeve board, showing the pivots;

Figure 8 is a perspective view of a portion of the smaller board, showing the pivots;

Figure 9 is a sectional view taken along 50 the lines 9—9 in Figure 7, showing the slide in the sleeve board.

A brief description of the drawings having 55 been given, a detailed description of the drawings will now follow in which like reference characters indicate corresponding parts thruout the drawings.

The numeral 10 indicates a cabinet in which my ironing board is mounted. This cabinet has a door 11 and inside wall portions 12, with a back portion 13. A board 14 is pivotally and slidably mounted in the cabinet by means of the cross-piece 15 being secured to the innermost end of the board 14 and with the ends thereof being pivotally and slidably mounted in the slots 39 in each 60 of the side wall portions 12 of the cabinet.

Some distance below the pivotal point of the board 14 there is another cross member 16 which is pivoted to the inside wall portions 12 of the cabinet 70.

Rigidly secured to the cross-member 16 is a board or support 17 which extends outwardly and upwardly and has a cross-piece 18 secured to its outer end. On the lower side of the board 14, and running longitudinally therewith are secured the guide members 19 and 20. These guide members near their outer surfaces have projections 21 and 22, and when these guide members are secured to the lower side of the board 14 they 75 form a recess for the reception and guidance of the cross-piece 18. A member 23 is secured to the outer ends of the members 19 and 20 and thus acts as a stop for the outward movement of the member 18 when the board is unfolded.

A button 37 is pivotally secured to the back 13, being mounted on the bolt 38 and when the board 14 is unfolded this button 37 is turned to vertical position, thus holding the board 14 rigidly in place.

Immediately above the pivot point of the large board 14 there are blocks 24 secured to the sides of the cabinet and to the back 13.

Secured to the end of the sleeve board 25 is the cross-piece 26 which has pivot points 27 and 28 on its ends which are pivotally mounted in the blocks 24. Immediately below the pivot points just described is another cross-member 29 which has pivot points 30 and 31 on its ends which are also pivoted in the blocks 24. Rigidly secured to the member 29 is an upwardly projecting member 32 which has a cross-piece 33 secured to the outward and upper end thereof, and this fits into a groove 34 cut in the lower side of the sleeve board 25 and running longitudinally thereof.

Secured at either side of this groove 34 110 and overlapping a portion of said groove are the strips 35 and 36. These strips when se-

cured in the manner described and shown form a guideway for the member 33 in which the member 33 slides when the board is swung on its pivot to closed or open position.

The cross-piece 15 has pivot members 15^B and 15^A on its two ends, and the cross-piece 16 has pivot members 16^A and 16^B thereon at both of its ends, all of these pivot members fitting into the side wall 12 of the cabinet, the pivot members 15^A and 15^B also being slidably mounted in the vertical slots.

The method of operation of my device is as follows:

15 The cabinet is mounted in the wall of a room and forms a part of the wall of the room when the door of the cabinet is closed. When it is desired to use the ironing board the door of the cabinet is opened and the 20 boards are shown pointing upward in folded position. The board 14 is pulled outwardly and downwardly and when this is done the member 18 slides in the groove between the members 19 and 20 until it reaches the member 23 which prevents its further travel. The pivots 15^A and 15^B also slide upwardly 25 in the slots 39 in the side walls 12. When it has reached this position the board 14 is in approximately horizontal position with 30 regard to the floor of the room.

When it is desired to use the sleeve board

25, it is unfolded in the same manner as that above described for the board 24, with the exception that the pivots 27 and 28 are mounted in round holes instead of slots as in 30 the case of the board 14.

It will thus be seen that I have devised a simple and strong ironing board, and one that is of such rugged structure as to render it less liable to wear and become inoperable. 40

Having thus fully described my invention, what I desire to protect and secure by Letters Patent is as follows:

A wall cabinet having parallel vertical side portions, vertical slots in the side portions, a cross-member having its end slidably mounted in the vertical slots, an ironing board fixedly secured to the said cross-member, a second cross-member pivotally secured to the wall portions at a point forward of 45 the vertical plane of the first cross-member, a support secured to the second cross-member, a cross-piece secured to the free end of the support, a guide-way on the lower face of the ironing board in which the cross-piece 50 is adapted to slide, and means for limiting the outward movement of the free end of the support.

In testimony that I claim the foregoing as my own I have hereunto set my hand, 55 this the 23rd day of December, 1925.

EDWARD T. MICKEY.
